UNITED STATES PATENT OFFICE.

FRANCISZEK SZMYT, OF COLLINSVILLE, OKLAHOMA.

BULLET-SHIELD.

1,270,343.

Specification of Letters Patent. Patented June 25, 1918.

Application filed September 12, 1917. Serial No. 190,962.

To all whom it may concern:

Be it known that I, FRANCISZEK SZMYT, a citizen of Russia, residing at Collinsville, in the county of Rogers and State of Oklahoma, have invented certain new and useful Improvements in Bullet-Shields, of which the following is a specification.

This invention relates to armor and has particular reference to a compound armor for resisting projectiles.

One object of the invention is to provide an improved form of non-metallic armor.

A second object of the invention is to provide an improved form of non-metallic armor so arranged and constructed that the shock of projectiles striking the armor will be absorbed and thus avoid injury to the vessel or body protected by the armor.

A third object of the invention is to provide an improved armor of this description which may be used in connection with a ship without affecting the flotation of the ship unduly.

With the above and other objects in view, as will be hereinafter apparent the invention consists in general of certain novel details of construction and combinations of parts hereinafter fully described, illustrated in the accompanying drawing and specifically claimed.

In the accompanying drawing, like characters of reference indicate like parts in the several views, and:-

Figure 1 is a vertical section taken through a portion of the side of the ship and showing the improved armor applied thereto.

Fig. 2 is a face view of a portion of the armor showing successive layers broken away in order to disclose the construction.

Fig. 3 is a perspective view, partly broken away, showing one embodiment of the armor for use in connection with individual persons.

In the embodiment of the armor shown in the accompanying drawings there is disclosed an inner layer 10 of rubber. This inner layer of rubber consists of a series of sheets 11 of resilient rubber having between them sheets 12 of reinforcing fabric, the whole being so vulcanized together as to form one body. It will be noted, especially from Fig. 1, that the innermost sheet has its lower end projecting downward as at 13 and that its upper end is also elongated

and extends over the tops of the remaining sheets 11. Covering the outermost of these sheets and extending down across the ends of the intermediate sheets 11 is a layer 15 of felted cotton 15'. This layer 15 also extends down as at 16 to cover part of the projecting portion 14 of the innermost sheet. On the outside of this cotton layer is a layer 17 of cork which has been boiled in oil until it is thoroughly saturated and comparatively soft. The portion 14 of the innermost sheet is brought forward over the cotton and cork sheets and extends down as at 18 over the upper part of the outer surface of the cork sheet. In like manner the portion 13 of the inner rubber sheet is bent back over the lower portions of the cork and cotton sheets as at 19. The same arrangement may be used all around the edges as indicated at 20 in Fig. 3 and suitable straps 21 may be used to hold the armor on the body or in the case of a ship S bolts 22 may be used to hold the armor on the side of the ship. Now referring especially to the armor for a ship it will be seen that the armor principally consists of the rubber which is of nearly equal specific gravity with the water, cotton and cork and that thereby any excess of the specific gravity of the rubber over water is neutralized by the deficit of the specific gravity of the cork and cotton from that of water.

Experiment has shown that an armor constructed in this manner is highly resistant to the penetration of projectiles and there has thus been provided a simple and efficient device of the kind described and for the purpose specified.

It is obvious that many minor changes may be made in the form and construction of the invention without departing from the material principles thereof. It is not therefore desired to confine the invention to the exact form herein shown and described but it is wished to include all such as properly come within the scope claimed.

Having thus described the invention, what is claimed as new is:-

A projectile resisting armor consisting of an inner layer of rubber inclosing a plurality of spaced sheets of reinforcing fabric whereby the rubber layer is also arranged in a plurality of sheets, the innermost rubber sheet being of greater dimensions vertically

than the remaining sheets, and an intermediate layer of felted cotton covering the outer rubber sheets and a portion of the lower extremity of the inner rubber sheet, 5 an outer layer of cork saturated in oil and covering the cotton layer, the upper and lower portions of the innermost rubber sheet enveloping the top and bottom portions of

the cotton and cork layers, and means to hold said layers together.

10

In testimony whereof I affix my signature.

FRANCISZEK SZMYT.
